UNITED STATES PATENT OFFICE

HENRY K. WACK, OF NEW BEDFORD, MASSACHUSETTS, ASSIGNOR TO JOHN I. PAULDING, INC., OF BEDFORD, MASSACHUSETTS, A CORPORATION OF MASSACHUSETTS

SHADE HOLDER

Application filed December 19, 1929. Serial No. 415,328.

This invention relates to a shade holder and more particularly to the provision of means for supporting and holding shades, reflectors and the like in a device of that character.

Shade holders as generally constructed are provided with a flange in which are mounted a plurality of set screws adapted to be screwed inwardly underneath the lip of a shade, reflector or similar member for supporting it in the holder. It is desirable in such cases that the set screws should be so mounted in the flange of the holder as to be incapable of lateral movement, otherwise their supporting function is lessened with the possibility that the fixture supported by them may drop out of the holder. Lateral movement of the set screws may also, when the holder is made of porcelain and is subjected to vibration, result in a cracking or breaking of the flange of the holder.

One of the principal objects of the invention is to provide means for holding and locking a set screw in the flange of a shade holder and for preventing any lateral movement thereof without interfering with its longitudinal movement when required.

Another object of the invention is the provision of means which is simple in construction and which may be mounted in the shade holder easily and rapidly to facilitate the assembling process.

Other objects of the invention will be more specifically pointed out and described herein after.

My invention contemplates in a shade holder a set-screw holding member adapted to be locked in a suitable opening in the flange of the holder by the set-screw itself. In the preferred form of the invention, the holding member comprises a body portion adapted to fit in a suitable opening in the flange of the shade holder and having on one side a portion adapted to overlie and engage the inner face of said flange and on the other side a lip for engaging the outer face of said flange. The opening in the said flange is of such size and shape that the insertion of the set screw through a threaded hole in the holding member locks that member in the said flange and at

the same time locks itself firmly against lateral movement.

In the accompanying drawings, for the purpose of illustrating the application of the invention, there is shown one embodiment thereof, in which Figure 1 is a side elevation of a shade holder provided with shade holding means constructed in accordance with my invention, a portion of the holder being broken away to show the interior construction; Fig. 2 is a bottom plan view thereof; Fig. 3 is an elevation of a portion of the flange of the holder showing the opening for receiving a set-screw holding member and set screw; Fig. 4 is a similar view with the set-screw holding member and set screw shown in transverse section mounted therein; Fig. 5 is a cross sectional view on line 5—5 in Fig. 3 and Fig. 6 comprises two views of the set-screw holding member, the left hand view being an end elevation and the right hand view a side elevation.

Referring to the drawings showing one embodiment of the invention, 10 designates a shade holder having a hub 12 adapted for mounting the holder on a lamp socket or other part of an electric fixture and having an annular flange 14 within which may be mounted a shade, reflector or other device. In the flange 14 of the shade holder are mounted radially a number of set screws 16 which may be turned inwardly to project under a lip or flange formed on the shade or other device for supporting it in the holder.

The flange 14 of the holder is provided with a plurality of through and through openings 18 each of which is substantially rectangular with its longitudinal axis parallel with the edge of the flange. In its lower edge, each opening has formed therein a central semi-circular depression 20 (Fig. 3). Mounted in each opening is a set-screw holding member having a body or main part 22 adapted to lie in said opening and having on its inner side a portion 24 turned downwardly to engage the inner face 26 of the flange 14 and on its outer side a turned up lip 28 for overlapping the upper edge of the opening 18 and the outer face 30 of the said flange. In the downwardly turned portion 24 is a threaded

hole 32, in the forming of which an annular lip 34 is produced on the outer face of that portion to extend the threaded portion of the hole 32 and thereby give a longer bearing surface for the set screw threaded there-through.

The set screw is threaded through the hole 32 in the holding member and lies partially in the semi-circular depression 20 in the opening 18, thereby forcing the body portion of the holding member upwardly into contact with the top wall of the opening 18 and holding it in that position with the lip 28 overlapping the outer face of the flange so that 10 so long as the set screw is in position, the holding member is locked within the opening by the said lip and cannot be withdrawn (Fig. 4). The opening 18 should be of a length just sufficient to permit the lipped end to be pushed through easily but not sufficiently long to permit lateral movement of the holding member therein. Preferably, the inner face of the flange of the holder is recessed at 36 below each opening to receive 20 the downwardly turned portion 24 of the holding member in order that there may be no projecting parts on the inner face of the flange. The side walls of the recess 36 also serve as additional means for locking the holding member against lateral movement in 30 the flange of the holder.

To prevent withdrawal of the set screw from the holding member after it is mounted therein, the inner end of the said screw may 35 be expanded outwardly in any suitable manner to form a lock. The outer end of each set screw is provided with a knurled head 38 and when the set screw is set up in operation, the head covers up and conceals to a 40 large extent the opening in the flange of the holder and the lip of the holding member in order that these parts shall not detract from the appearance of the holder.

In the drawings, I have shown the shade 45 holder as being provided with three set screws mounted in accordance with my invention which number is generally sufficient but more may be added if desired.

The mounting of the set screw in the shade 50 holder is extremely simple; all that is necessary being to insert in each opening a set-screw holding member by pushing the lipped end through the opening and then inserting the set screw into the opening and threading it 55 through the threaded hole which forces the lipped end of the holding member up into locking position. After the set screws have been inserted, their ends are expanded to prevent withdrawal from the holding member.

It will be observed that when the holding member is mounted in the opening in the flange of the holder with the set screw that lateral movement of the holding member is 60 effectively prevented and likewise lateral

movement of the set-screw. This is of importance especially in shade holders made of porcelain because it obviates all danger of cracking or breaking the flange which frequently results when the set screws are so mounted as to be capable of lateral movement.

It is to be understood that the foregoing embodiment of the invention is set forth merely for the purpose of illustrating the application of my invention which is not to be limited thereto since it may be embodied in various other forms of construction within the scope of the following claims.

What I claim is:

1. A shade holder having a flange provided with a through-and-through opening, a one-piece set-screw holding member mounted in said opening and having portions engaging the inner and outer faces respectively of said flange, one of said portions being provided with a threaded hole, and a set screw extending through said opening and said threaded hole.

2. A shade holder having a flange provided with a through and through opening, a set-screw holding member mounted in said opening and having portions engaging the inner and outer faces respectively of said flange, said portions being turned in opposite directions and one of said portions being provided with a threaded hole, and a set screw extending through said opening and said threaded hole.

3. A shade holder having a flange provided with a through and through opening, a set-screw holding member mounted in said opening and having a turned portion engaging the inner face of said flange and a lip engaging the outer face of said flange, said turned portion being provided with a threaded hole, and a set screw extending through said opening and said threaded hole.

4. A shade holder having a flange provided with a through and through opening, a set-screw holding member mounted in said opening and having a turned portion engaging the inner face of said flange and a lip engaging the outer face of said flange, said turned portion being provided with a threaded hole, and a set screw extending through said opening and said threaded hole; said opening being of such shape and size that said set screw locks said holding member in said opening and locks itself against lateral movement.

5. A shade holder having a flange provided with a through and through rectangular opening, one side of said opening having a semi-circular depression, a set-screw holding member mounted in said opening and having portions engaging the inner and outer faces respectively of said flange, one of said portions being provided with a threaded hole and a set screw extending through said

threaded hole and mounted in the semi-circular depression in said opening.

6. A shade holder having a flange provided with a rectangular through and through opening, a one-piece set-screw holding member mounted in said opening and having portions engaging the inner and outer faces respectively of said flange, one of said portions being provided with a threaded 10 hole, and a set screw extending through said opening and said threaded hole for locking said holding member within said opening.

7. A shade holder having a flange provided with a through and through opening, 15 a set-screw holding member mounted in said opening and having a turned portion engaging the inner face of said flange and a lip engaging the outer face of said flange, said turned portion being provided with a threaded 20 hole, and a set screw extending through said opening and said threaded hole, said set-screw serving to lock said holding member in said opening.

In witness whereof, I have hereunto set
25 my hand this eleventh day of December, 1929.

HENRY K. WACK.
